UNITED STATES PATENT OFFICE.

LEWIS H. BROOME, OF JERSEY CITY, NEW JERSEY.

PANE-CONNECTING MEANS.

Application filed July 19, 1924. Serial No. 727,022.

To all whom it may concern:

Be it known that I, LEWIS H. BROOME, a citizen of the United States, and resident of Jersey City, in the county of Hudson and State of New Jersey, have invented a new and Improved Pane-Connecting Means, of which the following is a full, clear, and exact description.

This invention has relation to devices for connecting angularly disposed panes and has particular reference to a means for connecting and sealing the meeting edges of glass panes, such as are employed in the construction of unframed show windows, show cases or the like, the said invention being in the nature of an improvement over my copending application Serial No. 723,024.

One of the outstanding objects of the present invention is to provide a connecting means for the meeting edges of glass panes which eliminates the necessity of bevelling said meeting edges and consequently does away with the time and labor incident to the bevelling operation which is essential at the present time to procure a weather-proof joint.

Another feature of the present invention resides in the provision of a sealing element which functions to engage within the re-entrant angle defined by the meeting edges of the panes irrespective of the relative angularity of the panes and which sealing element is impinged and maintained in active sealing relation to the meeting edges of the panes by the connecting means.

The invention furthermore contemplates an improvement in a connecting and sealing means for the meeting edges of glass panes which means is inexpensive to manufacture, produce and apply, which is comparatively simple in its construction and which is thoroughly reliable and efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a perspective view illustrating the pane connecting and sealing means in its applied position;

Fig. 2 is a fragmentary vertical sectional view therethrough taken approximately on the line indicated at 2—2 in Fig. 1;

Fig. 3 is a horizontal sectional view taken approximately on the line indicated at 3—3 in Fig. 1;

Fig. 4 is a similar view taken approximately on the line 4—4 of Fig. 1;

Fig. 5 is a perspective view of one of the outer angle clip members removed;

Fig. 6 is a fragmentary perspective view of one of the meeting edges of a pane illustrating the recesses for accommodating the clip stud.

Referring to the drawings by characters of reference A, A designates respective glass panes or panels which are adapted to be connected to each other and disposed at an angle by means of a connecting and sealing device which constitutes the present invention. The meeting edges B of the panes or panels A are provided with complementary recesses C in the contacting corners D defined by the inner surface of the pane or panel and the meeting edge B.

The connecting means includes inner and outer angle clips 10 and 11 the former comprising a pair of angularly disposed arms 12 and a connecting portion 13 and the latter a pair of angularly disposed arms 14 the inner ends of which are joined together and are preferably formed integral. The outer member 11 is provided at the juncture of the arms 14 with an inwardly projecting threaded stud 15 and the connecting portion or bight 13 of the inner member 10 is medially apertured as at 16 to receive therethrough the free end of the stud 15 after which the retaining nut 17 is threaded on the projecting end of the stud whereby the arms 12 and 14 may properly grip and maintain the panes A in connected relation. It is of course understood that the stem extends through the complementary aligned recesses C at the contacting corners D of the meeting edges B of the panes A. The studs 15 are provided at the ends which are attached to the outer clip members 11 with suitable anchoring heads 18 which are embedded in the juncture of the arms 14 when the member 11 is molded. The arms 14 at their juncture are provided at the apex of

the angle of their inner side faces with a vertical semi-circular groove 19 the purpose of which will be hereinafter described.

The sealing means constituting a part of the present invention consists of an elongated element such as a tube or rod 20 which is preferably of circular formation in cross section and adapted to snugly fit within the re-entrant angle defined by the meeting edges B of the panes. The sealing elements 20 have their opposite ends inserted within the semi-circular grooves 19 of adjacent clips with the terminals in abutting relation to the studs 15 so that when the retaining nuts 17 are screwed home, the grooved portions 19 of the outer clip members 11 embrace and impinge a portion of the periphery of the sealing elements against the meeting edges of the panes throughout the entire length of the sealing element. If desired a suitable plastic substance may be employed as a calking between the periphery of the sealing element 20 and the meeting edges of the panes although such is not deemed essential as the rounded periphery of the sealing element which of necessity seats itself in the angle produced by the meeting edges.

From the foregoing it will thus be seen that an extremely simple and inexpensive mode of connecting and sealing the meeting edges of glass panes or panels has been devised which eliminates the necessity of bevelling the meeting edges to procure a weatherproof joint.

I claim:

1. A device for connecting and sealing the meeting edges of angularly disposed panes comprising inner and outer angle clips each having a pair of angularly disposed arms, inwardly projecting threaded studs from the outer angle clip members, the said inner clip members having a central aperture receiving said studs, a nut threaded on said stud constituting means for connecting the inner and outer clip members and for drawing the same toward each other to effect the clamping of the arms of said clip members with respect to the panes whereby to cause

one corner of each meeting edge to be brought into contact and a sealing element of circular cross sectional configuration positioned between each adjacent pair of clips embraced at their opposite ends by the outer member of the angle clips and fitting within the re-entrant angle defined by the meeting edges of the panes.

2. A device for connecting and sealing the meeting edges of angularly disposed panes comprising inner and outer angle clips each having a pair of angularly disposed arms, inwardly projecting threaded studs from the outer angle clip members, the said inner clip members having a central aperture receiving said studs, a nut threaded on said stud constituting means for connecting the inner and outer clip members and for drawing the same toward each other to effect the clamping of the arms of said clip members with respect to the panes whereby to cause one corner of each meeting edge to be brought into contact and a sealing element of circular cross sectional configuration positioned between each adjacent pair of clips embraced at their opposite ends by the outer member of the angle clips and fitting within the re-entrant angle defined by the meeting edges of the panes the said contacting corners of the meeting edges having complementary aligned recesses through which the threaded studs extend.

3. A means for connecting and sealing the meeting edges of angularly disposed panes comprising a plurality of clips, each including inner and outer angle members, the former having a central aperture and the latter provided with an inwardly projecting threaded stud which extends through said aperture, a nut on the inner end of the threaded stud, said meeting edges of the panes each having aligned recesses for receiving the studs, and a cylindrical sealing element positioned between each adjacent pair of clips embraced at their opposite ends by the outer angle member of each clip and fitting within the re-entrant angle formed by said meeting edges of the panes.

LEWIS H. BROOME.
